FOLDING CHAIR

Walter H. Gillette, Louisville, Ky.

Application April 17, 1933. Serial No. 666,609

6 Claims. (Cl. 155—142)

The invention relates to folding chairs and has for its objects to provide new and useful improvements in chairs of this character.

An important object of the invention is to provide a folding chair in which provision is made for adequately reinforcing the chair seat against distortion and ultimate damage by continued use, thereby making it possible to construct the seat of relatively thin slats or a light

10 wooden panel.

A further object is to provide means whereby when in open position, the chair seat is yieldingly held against accidental displacement or tendency to collapse in the direction in which

15 the chair is folded.

A further object of the invention is to provide a folding chair of comparatively light weight and of rigid and durable construction in which few parts are employed and reinforcement obtained at the desired locations so as to adequately withstand prolonged usage. For example the chair back and front legs may together constitute a single unit, preferably of bent wood.

25 A further object is to provide a folding chair constructed so as to permit of complete nesting of the leg and seat elements when in folded position to obtain a maximum economy of space which is advantageous in stacking the folded chairs.

With such objects in view, as well as other advantages which may be incident to the use of the improvements, the invention consists in the use of the parts and combinations thereof 35 hereinafter set forth and claimed, with the understanding that the several necessary elements constituting the same may be varied in proportions and arrangement without departing from the nature and scope of the invention.

40 In order to make the invention more clearly understood there are shown in the accompanying drawing means for carrying the same into practical effect, without limiting the improvements, in their useful applications, to the particular constructions which, for the purpose of explanation, have been made the subject of illustration.

In said drawing,

50 Fig. 1 is a central vertical section through a folding chair constituting a preferred embodiment of the invention, the chair being illustrated in open position.

55 Fig. 2 is a front elevation of the chair in folded position.

Fig. 3 is a vertical section on line 3—3 of Fig. 2.

Fig. 4 is an enlarged fragmentary horizontal section on line 4—4 of Fig. 2.

Fig. 5 is an enlarged detail view in side elevation of the slotted portion of one of the rear leg members looking toward the inner side thereof.

Fig. 6 is a transverse section on line 6—6 of Fig. 4.

Referring to the drawing, 1 indicates an integral unitary U-shaped member preferably formed of bent wood but which may be constructed of metal, the upper closed portion 2 of said member constituting the chair back and the lower free ends of said member constituting the front legs 3. Suitable bracing elements, illustrated as crossed metal straps 4 or the like, may be provided and secured at their ends to the legs 3 to maintain the spacing of the latter and insuring against outward distortion due to the spring of the wood or metal of which the member 1 is constructed.

The upper part of the member 1 may be partially closed by an inserted panel 5 or the like to add to the comfort of the chair occupant.

The rear legs of the chair are indicated at 6 and are pivotally secured at their upper ends as at 7 to the U-shaped member 1. Said rear legs are preferably suitably spaced from one another and like the front legs are reinforced by corresponding rear brace or strap elements 8.

The chair seat is indicated generally at 9 and is illustrated as comprising a marginal frame including an integrally formed front frame member 10 having secured thereto a rear frame member 11. The seat panel 12, preferably constructed of relatively thin and light wood or slats, is secured in any desired manner to the frame member 10 and 11 and may include on its upper surface a cushion or pad 13. The described chair seat assembly is preferably pivotally mounted on the front legs of the chair and to this end I provide a single metal bar or rod 14 extending transversely and beneath the chair seat to support and reinforce the relatively thin seat or panel 12. The rod is provided with flattened portions 15 adjacent its outer ends which are secured by screws 16 to the lower surface of the frame member 10 and which insures against any tendency for the bar 14 to turn. The outer axially aligned ends 14a of the rod are not flattened but retain their cylindrical form and are mounted for pivotal movement, preferably in apertures 17 of bearing plates 18, one for each

end of the rod and which plates are rigidly secured as by bolts or rivets 19 to the front legs 3 of the chair. If desired the outer extremities of the rod 14 may be upset as shown at 20 to insure against displacement from the bearing plates after the chair has been assembled.

The bearing plates 18 for the rod are provided as preferred construction to promote the life of the chair, but it will be obvious that the opposite 10 pivotal extremities 14a of the rod may be directly journaled in suitably disposed recesses in the leg members 3 and the bearing plates omitted.

The central or median portion of the bar or rod 14 is preferably bent or offset upwardly 15 within said frame for a material portion of its length as best seen at 14b in Fig. 4 and at right angles to the plane of the flattened portions 15, so as to snugly engage and reinforce the relatively thin seat panel 12.

20 This offset construction and arrangement of the rod 14 insures against undue deformation or splitting of the chair seat, especially when occupied by persons of relatively heavy weight, and generally contributes to the strength, durability and long life of the chair.

25 The offset median portion of the bar or rod 14 is swaged at 14c as by stamping or clamping between suitable die members to impart a flattened portion which is substantially of I-beam configuration in cross-section as best seen in Fig. 6. The described deformation of the bar at this point augments the rigidity of the bar to resist downwardly imposed strains when the 30 chair is occupied. To this end the bar is preferably flattened as described in a plane at right angles to the outer flattened portion 15 of the bar. In the described manner a bar which is of relatively small cross-sectional diameter is swaged or stamped into a virtual girder design 35 and functions as such as resist strains and stresses during the use of the chair.

40 Each rear side edge of the chair seat frame is provided with a plate member 21 secured as at 22 to the chair seat frame or rim member 10, 45 said plate members each having an outwardly projecting stud or trunnion 23 designed for slideable movement in opposed longitudinal recesses 24 on the inner sides of the rear legs 6. As best seen in Fig. 5 the upper end of one or both 50 recesses 25 is slightly offset or diminished in width as indicated at 25, to provide a restricted portion intermediate the ends of the recess which yieldably opposes the movement of the 55 studs 23 when the chair is either opened or closed. Such construction guards against accidental collapse of the chair due to the studs 23 moving downwardly in the recesses 24, as for example when the chair is intentionally moved to folded position. The construction is such as 60 to require a slight exertion on the part of the user in folding the chair to move the studs 23 out of the reduced or offset portions 25 of the recesses or grooves 24.

65 In folding the chair it is merely necessary to grasp the chair back and seat and swing the latter upwardly on its pivotal bearings 14a in the direction of the arrow, Fig. 1. The resulting sliding movement of the studs 23 in the 70 grooves of the rear legs brings the front and rear legs together as shown in Figs. 2, 3 and 4, with the rear legs resting snugly against the flattened portions 15 of the rod 14 and between the front leg members 3 and the seat frame 10. The forward 75 location of the pivot points 14a in the front leg members 3 results in the chair seat

being confined within the front leg members 3 and also within the rear leg members 6, as best seen in Fig. 4. This affords complete nesting of the chair leg elements with the chair, within a minimum of space and permits stacking of a plurality of chairs evenly and within a small area.

80 In opening the chair for use the reverse procedure is followed, the seat being swung downwardly toward a horizontal position until the studs 23, sliding freely in grooves 24, reach and frictionally engage the reduced or offset portions 25 at the top of said recesses to be yieldably retained in adjusted open position. As will be obvious the movement of the chair seat 85 toward and away from the back and front legs 90 automatically controls the movement of the rear legs from open to closed position and vice versa.

What I claim is:

1. In a folding chair, the combination of a 95 pair of front legs and a pair of rear legs pivotally connected thereto, a chair seat having a marginal frame and a central panel secured thereto, said seat being slidably mounted in the rear legs, and a metal bar extending beneath 100 said chair seat and pivotally mounted at its ends in said front legs, said bar having flattened portions adjacent its ends to which the lower face of the marginal frame is secured, the median portion of said bar being offset upwardly 105 within said frame to engage and reinforce the central panel of the chair seat.

2. In a folding chair, in combination: a pair of front legs and a pair of rear legs pivotally connected thereto, a chair seat pivotally 110 mounted on said front legs, said rear legs having recesses on their inner sides, means carried by said chair seat for slidably engaging said recesses, each of said recesses having a restricted portion intermediate its ends to yieldably 115 maintain said slideable engaging means of the seat in position when the chair is open.

3. In a folding chair, in combination: a pair of front legs and a pair of rear legs pivotally connected thereto, a chair seat having a marginal frame and a central panel secured thereto, said seat being pivotally mounted on said front legs, said rear legs having recesses on their inner sides, means carried by said chair seat for slidably engaging said recesses, each of said 125 recesses having a restricted portion intermediate its ends to yieldably maintain said slideably 130 engaging means of the seat in position when the chair is open, and a round bar extending beneath said seat and having flattened portions 135 adjacent its ends to which the lower face of the frame is secured, the median portion of said bar being offset upwardly within said frame for a portion of its length to engage and reinforce the central panel of the chair seat, said flattened portions of said bar resisting any tendency for said bar to turn and displace the offset portion thereof from engagement with said panel.

4. In a folding chair, in combination: a pair of front legs and a pair of rear legs pivotally 140 connected thereto, a chair seat having a marginal frame and a panel secured thereto said seat being pivotally mounted on said front legs, said rear legs having recesses on their inner sides, means carried by said chair seat for slidably 145 engaging said recesses, and a round bar extending beneath said seat and having flattened portions adjacent its ends to which the sides of the frame are secured, the median portion of said bar being offset upwardly within said 150

frame and stamped into an I-beam in cross-section for a portion its length to engage and reinforce the panel of the chair seat.

5. In a folding chair, the combination of a pair of front legs and a pair of rear legs pivotally connected thereto, a chair seat having a marginal frame and a central panel portion secured thereto, said seat being slidably mounted in the rear legs, and a metal bar extending beneath 10 said chair seat and pivotally mounted at its ends in said front legs, said bar being secured to the lower face of the frame of said chair seat and offset upwardly within said frame to engage and reinforce the central panel of the 15 chair seat.

6. In a folding chair, in combination: a pair of front legs and a pair of rear legs pivotally

connected thereto, a chair seat having a marginal frame and a central panel secured thereto, said seat being pivotally mounted on said front legs, and having slidable engagement with said rear legs, and a round bar extending beneath said seat and having flattened portions adjacent its ends to which the lower face of the frame is secured, the median portion of said bar being offset upwardly within said frame for a portion of its length to engage and reinforce the central panel of the chair seat, said flattened portions of said bar resisting any tendency for said bar to turn and displace the offset portion thereof from engagement with said panel. 80 85 90
